DISPENSER

Eric M. Ilsemann, Newark, N. J.

Application October 3, 1936, Serial No. 103,938

6 Claims. (Cl. 312—84)

The present invention relates to a dispenser for dispensing rod-like articles. More particularly the present invention relates to a sanitary rotating drum dispenser for dispensing or vending articles such as toothpicks, cigarettes or the like.

A primary object of the present invention resides in the provision of a simple, inexpensive dispenser of the above mentioned character.

Another important object of the present invention resides in providing a dispenser for rod-like articles with a partition adapted to support the articles to be dispensed, to retain the articles in a dispensing drum as they are carried to a discharge point and provide a discharge chute for said articles.

A further object of the present invention resides in providing a dispenser of the above mentioned character with means for agitating the articles to align the same with the dispensing drum and supply them to the drum one at a time.

Another object of the present invention resides in providing a dispenser of the above mentioned character with means for preventing jamming of the articles in the dispensing drum.

A further object of the present invention resides in providing a dispenser of the above mentioned character with means to prevent the weight of the articles in the dispenser from effecting the articles at the drum supply opening and also prevent the arching and consequent jamming of the articles at the supply opening.

A further object of the present invention resides in supporting the dispensing drum of a dispenser of the above mentioned character on a stud between the opposite threaded ends in such a manner that the stud also serves as the operating shaft for the drum.

Further objects will appear as the description proceeds in connection with the appended claims and attached drawing wherein:

Figure 1 is a front elevational view of a dispenser made in accordance with the present invention;

Figure 2 is a transverse, vertical sectional view taken on line 2—2 of Figure 1.

With continued reference to the drawing wherein like reference numerals are used to designate the same parts in the several figures, the numeral 10 indicates the dispenser of the present invention in its entirety.

Dispenser 10 comprises an open ended, tubular sheet metal, body member 11, preferably of rectangular shape. The front wall 12 of member 11 adjacent its lower end is provided with a trans-

verse discharge opening 13 extending the full width of face 12. The opposite side walls 14 and 15 of body member 11, at a point above the level of opening 13, are provided with circular apertures 16 for a purpose to be hereinafter pointed out.

The lower end of member 11 is closed by a cup-shaped closure 17 which is connected to member 11 by spot welding as indicated at 18. A reinforcing plate 19 is secured to the center of closure 17 to strengthen the same in order that dispenser 10 may be connected to a suitable base 21. Base 21 may be of any suitable material but preferably takes the form of a rectangular wooden block as indicated in the drawing. Dispenser 10 is preferably connected to base 21 by a screw 22 which passes freely through suitable apertures 23 and 24 in base 21 and plate 19 and is secured in place by a nut 25 threaded thereon. Reinforcing beads 26 are die-pressed in body 11 or formed of any suitable metal and welded to body 11 to impart the desired transverse rigidity to the dispenser.

An agitator plate 27 is secured to the inner face of wall 12, adjacent the top of body member 11, in any suitable manner. Spot welding, indicated at 28, is preferably utilized to secure plate 27 along flat portion 29 to wall 12 as shown. Plate 27 below portion 29 is offset at 31 and provided with transverse corrugations 32 for a purpose to be presently described.

A partition member 33 having a vertically extending securing portion 34, a sloping article supporting portion 35, an article guiding portion 36, a discharge chute 37 and a securing portion 38 is also provided by the present invention. Guiding portion 36, as seen in Figure 2, is of generally circular configuration and is designed to loosely receive a dispensing drum 39.

Drum 39 is generally circular in cross-section and is provided with a plurality of longitudinally extending slots 40 of sufficient depth to receive a single article to be dispensed. Walls 41 of slots 40, as seen in Figure 2, are slightly shorter than walls 42 and the peripheral surface 43 of drum 39 is cut back on a small arc as at 44 to provide a smooth unbroken surface between slots 40 so that the articles will be disposed well down in slots 40. Drum 39 at its ends is provided with reduced hubs 45, as seen in Figure 1. Any suitable material, such as wood, sheet metal or the like, may be used for forming drum 39.

Drum 39 is preferably formed of wood and prior to the insertion of member 33 in member 11, an ejector element 47 comprising a single

strip of wire 48 bent to provide spaced hook-like portions 49 in its transversely extending portion 51 and offset leg portions 52 terminating in loops 53 is placed in position with loops 53 loosely receiving hubs 45. Drum 39 with ejector element 47 in place is then inserted in member 11 and secured in a manner to be hereinafter described. Member 33 is then inserted in member 11 and portion 36 thereof forced around drum 39. Portions 34 and 38 are then welded at 58 to rear wall 53 and the rear of wall 12 to securely fasten member 33 in place.

It will be noted that member 33 is of slightly less width than member 11 and as a consequence 15 a space 54 is provided between member 33 and and the walls 14 and 15 of member 11. Spaces 54 are designed to receive legs 52 of ejector 47, as seen in Figure 1. Hook-like portions 49 provide a receiver designed to catch the article 20 dispensed by drum 39.

Chute 37, as seen in Figure 2, terminates at 59 approximately midway of slot 13 and legs 52 of ejector 47 extend through slot 13 on either side of chute 37 with hook portions 49 disposed 25 in front of wall 12. Member 33 between portions 35 and 36 is provided with a downwardly curved portion 60 designed to cooperate with plate 27 and form a narrow opening for passage of said articles.

30 A suitable wood screw 61 is inserted through aperture 16 in wall 14 and threaded into the adjacent hub 45 of drum 39. An unthreaded portion 62 of a width corresponding to the thickness of wall 14 is provided on screw 61. Portion 62 35 provides a bearing surface for engagement with the wall of aperture 16. A stud 63 having an unthreaded portion 64 providing a bearing surface for engagement with aperture 16 of wall 15 is threaded into the other hub 45 of drum 39. A 40 knob 65 is threaded on the other end of stud 63 the knob being disposed on the outside of body member 11 and serving as the means for rotating drum 39 in dispensing the articles from dispenser 10. The threads on screw 61 and stud 63 45 are preferably all right-hand threads so that the rotation of drum 39 by means of knob 65 tends to more securely embed the screw and stud in the hubs 45 and knob 65.

The lowermost end 66 of plate 27 is provided 50 with a tab 67 and is designed to engage the periphery of drum 39. End 66 of plate 27 also extends below return curved portion 60 of member 33 to provide a supply aperture 69 designed to supply articles singly to slots 40 of drum 39. 55 From an inspection of Figure 2, it will be seen that aperture 69 is disposed below portion 60 at one side of drum 39. As a consequence the weight of the articles in dispenser 10 is prevented from acting upon the article in aperture 69 and 60 as a result the supply of a single article to slot 40 is assured.

A cup-like cover 71 is provided for closing the top of member 11 after the articles are deposited in member 11.

65 Toothpicks or other similar articles are placed in dispenser 10 by removing cover 71. The articles are placed in dispenser 10 with their longitudinal axes disposed transversely of member 33 and their ends slightly spaced inwardly of walls 70 14 and 15. It will be clear that the articles will pass into the space 72 between member 33 and plate 27 and that a single article will be received in aperture 69 which is of sufficient size to receive only one article. Upon rotation of drum 75 39, end 66 of plate 27 will drop into one of the

slots 40 and the article in aperture 69 will be supplied to slot 40. Tab 67 then cams end 66 of plate 27 out of the slot leaving the article therein.

At the same time plate 27 will be vibrated, due 5 to the movement of end 66 into and out of slot 40. This vibration will prevent the arching of the articles above aperture 69 and cause the articles to be properly aligned with aperture 69 due to their passage over corrugations 32. 10

As rotation of drum 39 is continued the article in slot 40 is carried around with drum 39 and held in slot 40 due to the close fit of portion 36 of member 33 with respect to the periphery of drum 39. At the same time the ends of the article in slot 40 which extend beyond the ends of drum 39 will be brought into engagement with legs 73 of loops 53 and forced out of or ejected from slot 40 as the slot clears portion 36 of member 33. The ejection of the article from slot 40 20 deposits the article upon chute 37. The article then passes along chute 37 under influence of gravity and out through slot 13 into the receiver formed by hooks 49 of ejector 47.

The invention may be embodied in other specific forms without departing from the spirit or essential characteristics thereof. The present embodiments are therefore to be considered in all respects as illustrative and not restrictive, the scope of the invention being indicated by the 30 appended claims rather than by the foregoing description, and all changes which come within the meaning and range of equivalency of the claims are therefore intended to be embraced therein. 35

What is claimed and desired to be secured by United States Letters Patent is:—

1. An article dispenser comprising a housing for receiving articles to be dispensed; a dispensing drum rotatably supported in said housing; a partition secured to opposite walls of said housing and sloping from one of said walls to said drum and from said drum to said other wall, said first mentioned sloping portion extending over said drum to support the articles 45 above said drum and having a circular portion between said sloping portions for surrounding a portion of said drum and retaining the articles to be dispensed in said drum and a plate secured to said housing and cooperating with said partition to deliver articles separately to said drum. 50

2. The combination defined in claim 1 wherein said container is provided with a discharge opening and said second mentioned sloping portion terminates at said opening to provide a discharge 55 chute.

3. The combination defined in claim 1 wherein said plate is secured adjacent the top of said housing and comprises a corrugated spring metal plate extending downwardly to a point below and adjacent said first mentioned portion of said partition to provide an article supply aperture at a point unaffected by the weight of the articles in said dispenser. 60

4. A dispenser for use in dispensing rod-like 65 articles comprising a container for said articles, a discharge chute in said container, means for selecting one of said articles and discharging it into said chute, a combined ejector and receiving receptacle consisting of a length of wire having 70 spaced hook shaped elements intermediate its ends forming a receptacle for said discharged articles, supporting legs extending into said container and receiving said chute therebetween and loops at the ends of said legs encircling a por- 75

tion of said means and operating to eject said articles from said means.

5. A dispenser for use in dispensing rod-like articles comprising an elongated box-like body having a transverse discharge opening in one of its walls adjacent the bottom thereof, a partition member having one end secured adjacent the top of the wall opposite said first mentioned wall, said partition sloping toward the center of 10 said body and having a downwardly curved portion near the center of said body and a substantially circular portion underlying said curved portion and terminating in a discharge chute, a spring metal plate secured to said first mentioned wall of said body adjacent the top thereof, said plate having transverse corrugations therein and a tip disposed below said curved portion of said partition, said partition and said plate cooperating to support said articles in said body and provide a supply opening below said curved portion and between said curved portion and said tip whereby an article supplied to said opening is relieved of substantially all downward pressure of said supported articles, a dispensing drum engaging said tip and having transverse slots for receiving an article from said supply opening, means for rotating said drum to cause said slots to engage said tip to vibrate said plate and cause an article to fall from said 25 supply opening into said slot and be carried around in said slot with its ends protruding be-

yond the ends of said slot, an ejector comprising wire loops disposed adjacent the ends of said slots for engaging the ends of said article and forcing it out of said slot onto said chute after said article reaches the end of said circular portion and spaced wire hooks integral with said loops disposed outside of said body and adjacent said discharge opening for receiving said article from said chute.

- 5
6. A dispenser for use in dispensing rod-like 10 articles comprising an open ended sheet metal housing having a discharge opening; a partition member diagonally disposed in said housing and providing a supporting portion, a circular guiding portion and a discharge chute; a dispensing 15 drum disposed in said guiding portion with a portion of said supporting portion extending completely over said drum; a vibrator plate disposed in said housing and having one end engaging said drum below said extending portion of said 20 supporting portion; means for rotating said drum to vibrate said plate and supply articles to said drum and discharge articles from said drum to said chute; and a one piece wire member having loops adjacent said drum for ejecting 25 articles from said drum and spaced hook shaped elements adjacent said discharge opening and outside of said housing for receiving articles from said chute.
